 land, a British company

Application February 25, 1935, Serial No. 7,971
 In Great Britain March 12, 1934

20 Claims. (Cl. 84—174)

This invention is for improvements in or relating to horizontal pianofortes and has for one of its objects to provide a construction which can be cheaply made, will occupy a minimum 5 of floor space and is of good tone.

According to the invention, there is provided a horizontal pianoforte in which the sounding-board is triangular, the keyboard runs along one of the sides thereof, and of the other two 10 sides, one is free to vibrate without contact with the sounding-board support, and the other is fixed to a straight length of fillet which is in turn fixed to a straight length of case, and the whole or substantially the whole of the sounding- 15 board bars are so arranged on the sounding-board as to be received at their ends by supports at the key-board side and the said fixed side of the triangle. The triangular shape of the sounding-board according to the present invention, 20 since it permits one of the sides to be fixed to a straight length of fillet and thereby to a straight length of case, enables important advantages to be attained in that the said straight portions of the fillet and case themselves have 25 resonating properties which are utilized. Heretofore this portion of the case has been of curved formation and by reason of this shape is incapable of adding to the sounding-board those resonating properties supplied by the straight length employed according to the present invention.

This is true also of a previously proposed construction in which the lid of a grand piano was to be made of substantially triangular contour said lid being in the shape of a right-angled triangle with a curved hypotenuse.

The sounding-board may be a perfect triangle or, in some circumstances, it may be preferred to have the angle of the triangle opposite to the said free side slightly truncated and the short 40 length of sounding-board at the truncation also left free to vibrate without contact with the sounding-board support.

In carrying out the present invention the general direction of the length of the portion or 45 portions of the contour of the sounding-board left free to vibrate without contact with the sounding-board support may be made to approximate to the general direction of the length of the strings of the pianoforte. With a sounding-board of wood, the sounding-board bars may be 50 so arranged that the direction of their length obliquely intersects the direction of the length of the grain of the sounding-board and the obliquity of the intersection and the closeness

of adjacent bars may be such that each bar intersects grain "lines" also intersected by the adjacent bar. The general direction of the length of the grain of the sounding-board may approximate to the general direction of the 5 length of the strings of the pianoforte.

In a preferred construction of pianoforte according to the present invention, the sounding-board is triangular with two sides at a right-angle or substantially a right-angle to each 10 other and the third side straight, the base strings are parallel (or substantially parallel) and adjacent to one of the right-angle sides which is free to vibrate without contact with the sounding-board support, the key-board runs 15 along the other right-angle side, and the third side is fixed to a straight length of case. In an alternative construction the base strings are parallel (or substantially parallel) to the hypotenuse of the triangle, the key-board being 20 along one of the right-angle sides and having the other right-angle side extending rearwardly from its right-hand end.

A further construction according to the invention is one in which the sounding-board is 25 of wood and is triangular with the key-board along one of the sides thereof and the strings, and the grain lines of the wood in the sounding-board, extending rearwardly from the key-board side to one of the other sides of the triangle which is straight and which lies at an acute angle to the key-board side. Thus, the grain lines in the sounding-board will be in a graded series corresponding approximately in 30 length to the vibration or "speaking" lengths 35 of the graded series of strings, and each string will be located close to a grain line of corresponding length. This construction will be found to produce a pianoforte of very fine tone.

According to another feature of the invention, 40 there is provided a horizontal pianoforte in which the case, as viewed in plan, is triangular and has the key-board along one side, the base strings parallel (or substantially parallel) and adjacent 45 to a second side and the hitch pins along the third side which is straight.

For a more complete understanding of the invention there will now be described, by way of example only and with reference to the accompanying drawings, certain constructional forms of pianoforte according to the invention. It is to be understood, however, that the invention is not restricted to the precise constructional details set forth.

In these drawings—

Figure 1 is a plan of a pianoforte according to the present invention with the lid removed;

Figure 2 is a view corresponding to Figure 1 but with the iron frame also removed;

Figure 3 is a side elevation of the parts shown in Figure 2 looking in the direction of the arrows 3 but with a portion of one side wall removed; in this figure the lid or top and its co-operating parts are shown in chain lines;

Figure 4 is a detail sectional view on the line 4—4 of Figure 2;

Figure 5 is a detail sectional view on the line 5—5 of Figure 2;

Figure 6 is a plan view on a scale smaller than that of the preceding figures showing the position of the pianoforte in the corner of a room;

Figure 7 is a view corresponding to Figure 2 but on a smaller scale and showing a modified construction;

Figure 8 is a detail sectional view on the line 8—8 of Figure 7 but on a scale larger than that of Figure 7, and.

Figures 9 and 10 are views corresponding to Figure 7 of other modified constructions.

Like reference numerals indicate like parts throughout the drawings.

Referring firstly to Figures 1 to 5, the iron frame is indicated at 28, the bridge at 21, the sounding-board at 22, the strings at 23 with their hitch pins at 230 and the underframe at 24. The case comprises three principal walls 25, 26 and 27, each of which is straight. The case is of the shape of a right-angled triangle with the acute angles truncated and closed by short pieces of case 28 and 29. Affixed to certain of the walls of the case and a part of the frame, all round the contour of the sounding-board 22 is a fillet 30 which constitutes the support for the sounding-board. The sounding-board bars are shown at 31. They are arranged parallel to each other and are housed in notches formed in the fillet 30. The sounding-board 22 is not affixed to the fillet 30 all the way round its contour. A free portion is left at the bass side between the points 32 and 33, and there is also a short free portion on the treble side between the points 34 and 35. Figure 5 shows the way in which the fillet 30 is cut back between the points 32 and 33. It is similarly cut back at the position 36 (see Figure 2). The edge 37 of the sounding-board 22 is also cut back between the points 32 and 33 so as to avoid contact with the wall 26 of the case. The advantage of having one or more portions of the sounding-board free to vibrate without contact with the sounding-board support is that the resonating properties of the sounding-board will be greatly enhanced and the tone of the instrument consequently improved.

The direction of the grain of the wood in the sounding-board 22 is indicated by the lines 38, and it will be seen that these lines obliquely intersect the sounding-board bars 31. Preferably the obliquity of the intersection and the closeness of adjacent bars are such that each bar 31 intersects grain "lines" also intersected by the adjacent bar. The grain lines are those seen on the surface of a board cut longitudinally of the tree and the lines are formed by the difference in the appearance of the spring and autumn growths. The vibrations are transmitted longitudinally along the grain lines, and it will, therefore, be appreciated that with the particular arrangement of the obliquity and the closeness of the bars just specified the vibrations

may be assumed to travel mainly in a zigzag path across the sounding-board due to the co-operation of the grain lines of the sounding-board and the grain in the bars which, of course, lies parallel to the direction of the length of the bars. This results in imparting to the instrument long resonance.

The lid or top is intended in this construction to be hinged to the wall 27 of the case whereby when it is raised it will reflect the sound waves very effectively. In the construction illustrated the angle between the walls 25 and 27 is about 42°. A convenient small instrument having this said angle, has the keyboard side about 51½ inches long and the other right-angle side about 48 inches long. If now this instrument is placed in a corner of a room, as indicated in Figure 6, it will be found that the floor space occupied by the instrument and by the person playing it will be less than that occupied when an upright pianoforte is in question.

It will be appreciated that the triangular shape has the advantage of permitting straight timber with the grain running along the length thereof to be employed in all parts. Timber from conifers can be used for the case and for the fillet 30 and the tone will be transmitted to all parts thereof.

A comparison of Figures 1 and 2 shows that it is possible to have the grain lines 38 in the sounding-board in a graded series corresponding approximately in length to the vibration or "speaking" lengths of the graded series of strings. That is to say, the lengths of the grain lines measured from the keyboard side to the hypotenuse of the sounding-board can be approximately the same as the free lengths of the strings extending from the bridge 21 towards the keyboard. Further, each string and its corresponding grain line can be close to one another so that there will be a substantial sympathetic vibration of the grain lines supplementing the vibrations transmitted through the bridge 21. In this way the advantages mentioned above will be attained.

The pianoforte according to the present invention can be made in any desired size from, say, a full concert "grand" pianoforte down to a small instrument as mentioned above, and any suitable angles may be chosen for the triangular formation according to circumstances. The triangular shape of itself enables increased string length to be obtained as compared with an orthodox grand pianoforte or baby grand pianoforte. If it is desired to obtain still longer strings, the arrangements shown in Figures 7 to 10 may be employed. In the construction shown in Figure 7 the wall 39 is considerably longer than the wall 40. This enables a very long free edge to be left on the sounding-board if desired beside the wall 39. In some cases, particularly with large pianofortes, it may be advantageous to stiffen the edge by a flange 41 or other reinforcing member extending along it. This flange 41 could be free from contact with the case except possibly at its ends.

Figure 9 shows another construction in which long bass strings can readily be obtained and a long free edge for the sounding-board if desired. In this construction the key-board wall 42 has the other right-angle wall 43 at its right-hand end. There may be a long free edge to the sounding-board adjacent to the wall 44 and a further free portion is indicated between the points 45 and 46 along the wall 43. The construction shown in this figure will entail crank-

ing of parts of the "action" and in view of this may not be found so advantageous as the other constructions.

The construction shown in Figure 10 is very similar to that shown in Figure 7 except that the angle between the key-board wall 47 and the wall 48 on its left is an obtuse angle.

It is to be understood that the invention is not restricted to the precise constructional details set forth.

I claim:—

1. In a horizontal pianoforte, a sounding-board support, a triangular sounding-board having all of its sides straight, means for mounting the sounding-board on said support so that the key-board runs along one of the sides of the sounding-board and so that another side of the latter is free to vibrate without contact with the sounding-board support, a straight length of case, a straight length of fillet which is fixed thereto and to which is fixed the third side of the sounding-board, sounding-board bar supports disposed at the key-board side and the said fixed side of the triangle, and sounding-board bars so arranged on the sounding-board as to be received at their ends by said sounding-board bar supports.

2. In a horizontal pianoforte, a triangular sounding-board having all of its sides straight, a sounding-board support, means for mounting the sounding-board thereon with one of its sides substantially parallel to the length of the key-board and a second side free to vibrate without contact with the sounding-board support, a straight length of case, a straight length of fillet which is fixed thereto and to which is fixed the third side of the sounding-board, sounding-board bar supports disposed at the key-board side and the said third side of the triangle and sounding-board bars so arranged on the sounding-board as to be received at their ends by said sounding-board bar supports.

3. In a horizontal pianoforte, a triangular sounding-board having all of its sides straight and having one of its angles slightly truncated, a sounding-board support, means for mounting the sounding-board thereon so as to have the keyboard running along one of its sides which is adjacent to the said truncated angle and to have the side opposite to the said truncated angle and the short length of sounding-board at the truncation left free to vibrate without contact with the sounding-board support, a straight length of case, a straight length of fillet which is fixed thereto and to which is fixed the third side of the sounding-board, sounding-board bar supports disposed at the key-board side and the said third side of the triangle and sounding-board bars so arranged on the sounding-board as to be received at their ends by said sounding-board bar supports.

4. In a horizontal pianoforte, a triangular sounding-board having all of its sides straight, a sounding-board support, means for mounting the sounding-board thereon with one of its sides disposed substantially parallel to the length of the key-board, and with a second side free to vibrate without contact with the sounding-board support, the general direction of the length of which second side approximates to the general direction of the length of the pianoforte strings, a straight length of case, a straight length of fillet which is fixed thereto and to which is fixed the third side of the sounding-board, sounding-board bar supports disposed at the key-board side and

the said third side of the triangle and sounding-board bars so arranged on the sounding-board as to be received at their ends by said sounding-board bar supports.

5. In a horizontal pianoforte, a triangular sounding-board having all of its sides straight, a sounding-board support, means for so mounting the sounding-board thereon that one of its sides is disposed at the side of the key-board and so that a second side is free to vibrate without contact with the sounding-board support, which sounding-board has the angle of the triangle opposite to the said second side slightly truncated and the short length of sounding-board at the truncation also left free to vibrate without contact with the sounding-board support, with the general direction of the length of the free portion at the truncation and of the said second side approximating to the general direction of the length of the pianoforte strings, a straight length of case, a straight length of fillet which is fixed thereto and to which is fixed the third side of the sounding-board, sounding-board bar supports disposed at the key-board side and the said third side of the triangle and sounding-board bars so arranged on the sounding-board as to be received at their ends by said sounding-board bar supports.

6. In a horizontal pianoforte, a triangular sounding-board of wood having all its sides straight, a sounding-board support, means for mounting the sounding-board thereon with the key-board running along one of its sides and with another side free to vibrate without contact with the sounding-board support, a straight length of case, a straight length of fillet which is fixed thereto and to which is fixed the third side of the sounding-board, sounding-board bar supports disposed at the key-board side and the said fixed side of the triangle, and sounding-board bars having their ends received by said sounding-board bar supports and so arranged on the sounding-board that the direction of their length obliquely intersects the direction of the length of the grain of the sounding-board.

7. In a horizontal pianoforte, a triangular sounding-board of wood having all its sides straight, a sounding-board support, means for mounting the sounding-board thereon with the key-board running along one of its sides and with another side free to vibrate without contact with the sounding-board support, a straight length of case, a straight length of fillet which is fixed thereto and to which is fixed the third side of the sounding-board, sounding-board bar supports disposed at the key-board side and the said fixed side of the triangle, and sounding-board bars having their ends received by said sounding-board bar supports and so arranged on the sounding-board that the direction of their length obliquely intersects the direction of the length of the grain of the sounding-board, and so that the obliquity of the intersection and the closeness of adjacent bars are such that each bar intersects grain lines also intersected by the adjacent bar.

8. In a horizontal pianoforte, a triangular sounding-board of wood having all its sides straight, a sounding-board support, means for mounting the sounding-board thereon so as to have the key-board running along one of its sides and to have another side free to vibrate without contact with the sounding-board support, the general direction of the length of which free side approximates to the general direction

of the length of the pianoforte strings, a straight length of case, a straight length of fillet which is fixed thereto and to which is fixed the third side of the sounding-board, sounding-board bar supports disposed at the key-board side and the said fixed side of the triangle, and sounding-board bars received at their ends by said sounding-board bar supports and so arranged on the sounding-board that the direction of their length obliquely intersects the direction of the length of the grain of the sounding-board.

9. In a horizontal pianoforte, a triangular sounding-board of wood, a sounding-board support, means for mounting the sounding-board thereon with the keyboard running along one of its sides and with another side free to vibrate without contact with the sounding-board support, the general direction of the length of the grain of which sounding-board approximates to the general direction of the length of the pianoforte strings, a straight length of case, a straight length of fillet which is fixed thereto and to which is fixed the third side of the sounding-board, sounding-board bar supports disposed at the key-board side and the said fixed side of the triangle, and sounding-board bars so arranged on the sounding-board as to be received at their ends by said sounding-board bar supports.

10. In a horizontal pianoforte, a triangular sounding-board of wood, a sounding-board support, means for mounting the sounding-board thereon so as to have the key-board running along one of its sides and to have another side free to vibrate without contact with the sounding-board support, the general direction of the length of the grain of which sounding-board approximates to the general direction of the length of the pianoforte strings, a straight length of case, a straight length of fillet which is fixed thereto and to which is fixed the third side of the sounding-board, sounding-board bar supports disposed at the key-board side and the said fixed side of the triangle, and sounding-board bars received at their ends by said sounding-board bar supports and so arranged on the sounding-board that the direction of their length obliquely intersects the direction of the length of the grain of the sounding-board.

11. In a horizontal pianoforte, a triangular sounding-board having two straight sides at substantially a right-angle to each other and the third side straight, a sounding-board support, means for mounting the sounding-board thereon with one of its right-angle sides left free to vibrate without contact with the sounding-board support, pianoforte strings, means for mounting said strings so that the bass strings are substantially parallel to and adjacent to the said free right-angle side of the sounding-board a key-board running along the other right-angle side of the sounding-board, a straight length of case, a straight length of fillet which is fixed thereto and to which is fixed the third side of the sounding-board, sounding-board bar supports disposed at the key-board side and the said third side of the triangle, and sounding-board bars so arranged on the sounding-board as to be received at their ends by said sounding-board bar supports.

12. In a horizontal pianoforte, a triangular sounding-board having two straight sides substantially at a right-angle to each other and the third side straight, a sounding-board support, means for mounting the sounding-board thereon with its hypoteneuse left free to vibrate with-

out contact with the sounding-board support, pianoforte strings, means for mounting said strings so that the bass strings are substantially parallel to and adjacent to the hypoteneuse of the sounding-board, a key-board running along that one of the right-angle sides of the sounding-board which has the other right-angle side extending rearwardly from its right-hand end, a straight length of case, a straight length of fillet which is fixed thereto and to which is fixed the said other right-angle side of the sounding-board, sounding-board bar supports disposed at the key-board side and said other right-angle side of the triangle and sounding-board bars so arranged on the sounding-board as to be received at their ends by said sounding-board bar supports.

13. In a horizontal pianoforte, a sounding board in the form of an obtuse-angled triangle, a sounding-board support, means for mounting the sounding-board thereon so as to have the key-board running along that one of its sides which has the obtuse angle contained between it and the side on its left and to have a second side free to vibrate without contact with the sounding-board support, a straight length of case, a straight length of fillet which is fixed thereto and to which is fixed the third side of the sounding-board, sounding-board bar supports disposed at the key-board side and the said third side of the triangle and sounding-board bars so arranged on the sounding-board as to be received at their ends by said sounding-board bar supports.

14. In a horizontal pianoforte, a triangular sounding-board of wood, a sounding-board support, means for mounting the sounding-board thereon with the key-board running along one of its sides and with a second side free to vibrate without contact with the sounding-board support, pianoforte strings, means for mounting said strings, with the strings and the grain lines of the wood of the sounding-board so arranged as to extend rearwardly from the key-board side to one of the other sides of the triangle which is straight and which lies at an acute angle to the key-board side, a straight length of case, a straight length of fillet which is fixed thereto and to which is fixed the third side of the sounding-board, sounding board bar supports disposed at the key-board side and the said third side of the triangle, and sounding-board bars so arranged on the sounding-board as to be received at their ends by said sounding-board bar supports.

15. A horizontal pianoforte comprising a case which is triangular as viewed in plan, a keyboard along one side of the case, pianoforte strings, means for mounting said strings within the case with the bass strings substantially parallel to and adjacent to a second side of the case, hitch pins along the third side of the case which is straight, a triangular sounding-board having all of its sides straight, means for mounting the sounding-board within the case so as to have the key-board running along one of its sides and to have another side free to vibrate without contact with the case, a straight length of fillet, means fixing said straight length of fillet to the said third side of the case, means fixing the third side of the sounding-board to said straight length of fillet, sounding-board bar supports disposed at the key-board side and the said fixed side of the sounding-board, and sounding-board bars so arranged on the sounding-board as to be re- 75

ceived at their ends by said sounding-board bar supports.

16. In a horizontal pianoforte, a triangular sounding-board having all of its sides straight, a sounding-board support, means for mounting the sounding-board thereon so as to have the key-board running along one of its sides and to have another side free to vibrate without contact with the sounding-board support, a reinforcing member extending along said free side to stiffen the latter, a straight length of case, a straight length of fillet which is fixed thereto and to which is fixed the third side of the sounding-board, sounding-board bar supports disposed at the key-board side and the said fixed side of the triangle and sounding-board bars so arranged on the sounding-board as to be received at their ends by said sounding-board bar supports.

17. A horizontal pianoforte comprising a case, a key-board extending along a side thereof, a lid or top hinged to a side other than the key-board side of the case, pianoforte strings, means for mounting said strings within the case, a triangular sounding-board having all of its sides straight, a sounding-board support within the case, means for mounting the sounding-board on said support so as have the key-board running along one of its sides and to have another side free to vibrate without contact with the sounding-board support, a straight length of fillet, means fixing said straight length of fillet to a straight length of the case, means fixing the third side of the sounding-board to said straight length of fillet, sounding-board bar supports disposed at the key-board side and the said fixed side of the triangle and sounding-board bars so arranged on the sounding-board as to be received at their ends by said sounding-board bar supports.

18. A horizontal pianoforte comprising a case, a key-board along one side thereof, pianoforte strings, means for mounting said strings within the case, a triangular sounding-board having all of its sides straight, a sounding-board support which includes a fillet affixed to the said case, means for mounting the sounding-board on the support so as to have the key-board running along one of its sides and to have another side free to vibrate, said fillet being so shaped as to be clear from contact with the sounding-board at the said portion of the contour of the latter

which is free to vibrate, a means fixing a straight length of said fillet to a straight length of the case, means fixing the third side of the sounding-board to said straight length of fillet, sounding-board bar supports disposed at the key-board side and the said fixed side of the triangle, and sounding-board bars so arranged on the sounding-board as to be received at their ends by said sounding-board bar supports.

19. A horizontal pianoforte comprising a case, a key-board along a side thereof, pianoforte strings, means for mounting said strings within the case, a triangular sounding-board having all of its sides straight, a sounding-board support within the case, means for mounting the sounding-board on said support so as to have the key-board running along one of its sides and to have another side free to vibrate without contact with the sounding-board support, a straight length of fillet, means fixing said straight length of fillet to a straight length of the case, means fixing the third side of the sounding-board to said straight length of fillet, sounding-board bar supports disposed at the key-board side and the said fixed side of the triangle and sounding-board bars so arranged on the sounding-board as to be received at their ends by said sounding-board bar supports.

20. A horizontal pianoforte comprising a case, a key-board along a side thereof, pianoforte strings, means for mounting said strings within the case, a sounding-board support mounted within the case, a triangular sounding-board having all of its sides straight and having one of its angles slightly truncated, means for mounting the sounding-board on said support so as to have the key-board running along one of its sides which is adjacent to the said truncated angle and to have the side opposite to the said truncated angle and the short length of sounding-board at the truncation left free to vibrate without contact with the sounding-board support, a straight length of fillet, means fixing said straight length of fillet to a straight length of the case, means fixing the third side of the sounding-board to said straight length of fillet, sounding-board bar supports disposed at the key-board side and the said fixed side of the triangle, and sounding-board bars so arranged on the sounding-board as to be received at their ends by said sounding-board bar supports.

ALBERT ARTHUR DALE.
